UNITED STATES PATENT OFFICE.

DAVID M. CARR, OF BROOKLYN, NEW YORK.

SIPHON APPARATUS.

Application filed April 7, 1921. Serial No. 459,402.

To all whom it may concern:

Be it known that I, DAVID M. CARR, a citizen of the United States, and resident of Brooklyn, in the county of Kings and State 5 of New York, have invented a certain new and useful Siphon Apparatus, of which the following is a specification, the same being a full, clear, and exact description of the invention, such as will enable others skilled in 10 the art to which it appertains to make and use the same.

This invention relates to improvements in plumbing devices and especially to means for providing a suitable, efficient and reliable 15 article composed of but few parts and which may be readily kept in order and repaired when necessary and which may also be easily attached to the water supply and also to the waste or drainage pipes of receptacles adapt- 20 ed to contain water or other liquids.

The invention resides also in valve mechanism preferably automatically controlling the flushing or draining of a container for liquids, which valve mechanism may also be 25 actuated by the direction of the flow of water or other liquid passing through the same, the said flow of the liquid serving under proper conditions to allow the flowing movement to commence a siphonic action.

With the above objects, and others which will be set forth below, the invention consists 30 in the construction, arrangement and operation of parts hereinafter described.

In the drawings, illustrative of one embodiment of the invention, which accompany and form a part of this specification,

Figure 1 represents an elevation of an apparatus constructed according to my invention;

Figure 2 is a view in section of my drainage tube;

Figure 3 is a section of another device in which my invention is embodied;

Figure 4 is a longitudinal section and Figure 5 is a plan view of my plug stopper showing the lower parts thereof in dotted lines, Figure 4 being taken on the line 4-4 Figure 5;

Figure 6 is a transverse section taken on 50 the line 6-6 Figure 4; and

Figure 7 is an enlarged view of the lower portion of the outlet tube 9.

Referring specifically by reference characters to the drawings the numeral 1 denotes 55 a suitable receptacle, as a wash tub, and 2 a container of any desired or approved char-

acter, as a washing machine. The said receptacle may be provided with a water supply as a faucet 3 and an outlet orifice as 4. I preferably provide the said receptacle with 60 a waste or outlet pipe 9 which may be made so as to be of varying heights as by the employment therewith of preferably telescopic tubes 10 and 10' in order that the height of the liquid in the receptacle may be maintained at any desired point. In connection with the same, I use an outlet or drain pipe having a body portion 6 of such size as to enable the cover 8 of the same to fit the outlet 4 and consequently enabling the same to 70 be substituted at will for the ordinary plug stopper commonly used.

The body portion 6 is constructed and arranged to make a hermetically sealed joint with the outlet 4 of the receptacle and the 75 cover 8 thereof is designed to make a hermetically sealed joint with the body portion 6. The pipe 9 communicating with the interior of the body 6 is attached to the cover 8 constructed and arranged to snugly but de- 80 tachably fit into the top of the said body.

From the body 6 and communicating with the interior thereof depend a plurality of tubes 7 which are preferably of such a size as to pass through the cross bars which are 85 ordinarily positioned at the orifice 4. The tubes 7 may be circular in cross section, or, in order to secure greater capacity of the same, may be made practically segmental in cross section so as to conform with the divisions of the said orifice by the cross bars as shown by the tubes 7' in Figure 5. These depending tubes of the outlet plug may be screwed into the same so that they may be moved up or down or permanent longer 90 or shorter tubes could be substituted therefor to effect the adjustment of their length below the plug in order that the same may be adapted to discharge the liquid at varying 95 distances below the bottom of the receptacle 1.

The container 2 has the ordinary outlet orifice 5 for drainage purposes and in order to avoid the necessity of catching the discharged liquid in pails or pans and then 105 emptying the same, I employ the following mechanism:

The outlet or drainage tube as 11 of a drainage device 13 is inserted in the said outlet orifice 5 thereby securely attaching 110 the same to the receptacle 2, the ordinary stopper for the said orifice having been re-

moved. At the opposite end of the tubular body 13 is inserted in the same a discharge tube 12, the said body portion being preferably detachable from the said two end tubes. 5 In the body portion 13 is located a valve ordinarily comprising two members 17 and 18 and preferably hinged to the body as at 19.

The valve may comprise two angularly arranged arms 17 and 18, and the valve member 17 may occupy three positions and may lie (1) in a line indicated as at 20, the valve member 18 lying at this time in a line designated as 21; or (2) the valve member 17 may be at the line 22 and the member 18 at the line 23; or (3) the valve members may be held in a position intermediate to those described as shown in full lines in the drawings, and by the use of a manually actuated thumb screw 24 the valve members, 20 by the engagement thereof of the said thumb screw, may be held fast in either of the three said positions at will. The body 13 is also provided with a side opening comprising the pressure tube 14, which latter tube and the faucet 3 may be connected by a flexible feed hose or tube 15, and the tube 12 and the drainage pipe 10 may be connected by means of the siphon tube 16.

The function of the thumb screw 24 is to 30 hold the valve 17-18 in any desired position so as to allow a greater or less amount of the liquid to pass therethrough.

In cases where it is not desired or convenient to attach the tube 11 directly to the 35 container 2 the ordinary plug stopper may be inserted in its place in the container 2 and the drainage attachment may be submerged in the container, in which instance the tube 11' may be left open as shown in Figure 3, 40 an extension 26 of the end thereof being preferably provided with orifices 26' to allow the liquid to freely enter the said tube, especially in cases where the opening of the tube 11' should happen to rest upon the bottom of the container. In this instance the tubes 12' and 14' of the body portion 13' 45 may be respectively attached to the sections of hose 15 and 16. If liquid under pressure from the faucet 3 is admitted through the tube 14 by the tube 15 the valve 17-18 will be pushed into the position indicated by the lines 20-21 permitting the liquid to flow from the faucet through the circulation or feed tube 15 and out through the tubes 14 and 12. When the pressure is shut off by 55 closing the faucet again the valve member 18-17 will be forced into a position that will close the side pressure tube 14 as shown by the dotted lines 22 and 23 in the drawings, 60 as the former flow ceases and a flow is established by gravity from the container 2 through the drainage tube 11 and discharge tube 12 and siphon tube 16 until the container is emptied.

65 If the level of the liquid in the waste pipe

10 is lower than that of the liquid in the container 2 in which the device 13' is immersed, or to which the body 13 is attached, the air pressure acting on the two levels will—when the current ceases to flow from the faucet 3 and pipe 15 through the tubes 14-12 by shutting off the supply entering the tube 14 as by turning off the faucet 3, or otherwise, at any desired point in the supply line—force the members 17 and 18 of the two membered valve into the position indicated by the lines 22 and 23 (or force the valve 17' from the line 20' to the position shown by the line 23') and siphon the liquid by gravity through the tubes 11 and 12 (or, if immersed, through the tubes 11' and 12') and then through the connecting siphon tube 16 to the desired outlet (as at 9, 10 and 10') for the liquid. It will be noted that this siphonic action takes place without disturbing or mixing with any liquid that may be held by the receptacle 1.

As long as the waste pipe connected with the hose 16 and leading from the tube 12 is higher than the level of the liquid in the container 2, after the said siphonic action the said pipe will act as a stop. The cylindrical body 13 may be removed at any time by merely unscrewing the same from the container and inserting the original plug or stopper for the waste outlet. At the lower portion of the tube 9 is located a projecting arm having an opening 30 equipped with a valve closing the said outlet tube or the side opening 30 thereof at will. By the use of this device the contents of the container may be either discharged through the valve into the elongated plug stopper 6 or they may be passed through the tube 9 and side outlet 30 into the receptacle 1 according to which way the said valve is turned. By the use of longer or shorter tubes 7 of the outlet plug 6 the liquid may be discharged at varying distances below the bottom of the receptacle, thus providing a lower level in the said discharge pipe than that of the said bottom.

It will be seen that the waste pipe of the receptacle 1 as used by me practically comprises a continuation of the siphon tube or line thereby securing a lower discharge level of the liquid.

I wish it to be understood that I do not desire to be limited to the particular use or the exact details of construction shown and described, for obvious modifications will occur to persons skilled in the art.

What I claim as my invention is:—

1. In a device of the class described, a container, a drainage tube having three spaced openings of substantial equal area, one communicating with the container and one with a faucet and the other comprising a discharge tube, a siphon tube connected with the discharge tube, and automatic liquid control means to cause liquid under pressure

5 entering the said opening communicating with the faucet to pass through the same into the discharge tube, and, when the flow of the liquid under pressure is cut off, to cause a flow of the liquid to be set up by gravity through the drainage and discharge tubes and the siphon tube, whereby the liquid in the container may be discharged.

2. In a device of the class described, a 10 container, a drainage tube having three spaced openings of substantial equal area, one communicating with the container and one with a faucet and the other comprising a discharge tube, a siphon tube connected 15 with the discharge tube, and automatic liquid control means to cause liquid under pressure entering the said opening communicating with the faucet to pass through the same into the discharge tube, and, when 20 the flow of the liquid under pressure is cut off, to cause a flow of the liquid to be set up by gravity through the drainage and discharge tubes and the siphon tube, whereby the liquid in the container may be discharged, in combination with a manually 25 actuated device to temporarily hold the said automatic means in any desired operative position.

3. In a device of the class described, a 30 container, a drainage tube having openings of substantially equal area at the ends and one side thereof and having one end communicating with the container and the other end comprising a discharge tube, a siphon 35 tube connected with the discharge tube, and liquid control means to cause liquid under pressure entering the said side opening to pass through the same into the discharge tube, and, when the flow of the liquid under 40 pressure is cut off, to cause a flow of the liquid to be set up by gravity through the drainage and discharge tubes and the siphon tube, the said control means comprising a device to control two of said openings embodying a valve consisting of a pair of angularly positioned arms respectively arranged to first close the drainage tube of the container and to open the said side opening, and afterward to open the said drainage tube 45 and to close the side opening.

4. In a device of the class described, a container, a drainage tube having openings of substantially equal area at the ends and one side thereof and having one end communicating with the container and the other end comprising a discharge tube, a siphon tube connected with the discharge tube, and liquid control means, comprising a device to control two of said openings embodying a valve 50 consisting of a pair of angularly positioned

arms respectively arranged to first close the drainage tube of the container and to open the side opening, and afterward to open the said drainage tube and to close the side opening.

5. In a device of the class described, a container, a drainage tube having openings of substantially equal area at the ends and one side thereof and having one end communicating with the container and the other end comprising a discharge tube, a siphon tube connected with the discharge tube and having means to lengthen the outlet thereof, and automatic liquid control means to cause liquid under pressure entering the said side opening to pass through the same into the discharge tube, and, when the flow of the liquid under pressure is cut off, to close the said side opening.

6. In a device of the class described, a container, a drainage tube having openings of substantially equal area at the ends and one side thereof and having one end communicating with the container and the other end comprising a discharge tube, a siphon tube connected with the discharge tube and having means to lengthen the outlet thereof, and automatic liquid control means, comprising a device to control two of said openings, to cause liquid under pressure entering the said side opening to pass through the same into the discharge tube, and, when the flow of the liquid under pressure is cut off, to close the said side opening.

7. In a device of the class described, a receptacle, an outlet therefor, a container, a drainage tube having openings of substantially equal area at the ends and one side thereof and having one end communicating with the container and the other end comprising a discharge tube, a siphon tube connected with the discharge tube and leading to an outlet in the receptacle, and liquid control means, comprising a device to control two of said openings, to cause liquid under pressure entering the said side opening to pass through the same into the discharge tube, when the flow of the liquid under pressure is cut off, to close the said side opening and open the drainage tube of the container, the said outlet having means whereby the liquid discharged from the container may be either emptied into the receptacle or caused to flow directly into the waste pipe thereof at will.

Signed at New York in the county of New York and State of New York this 4th day of April A. D. 1921.

DAVID M. CARR.
